UNITED STATES PATENT OFFICE.

HARRY H. GARDNER, OF JOHNSTOWN, PENNSYLVANIA.

WRENCH.

1,257,077.

Specification of Letters Patent. Patented Feb. 19, 1918.

Application filed February 8, 1917. Serial No. 147,453.

To all whom it may concern:

Be it known that I, HARRY H. GARDNER, a citizen of the United States, residing at Johnstown, in the county of Cambria and State of Pennsylvania, have invented certain new and useful Improvements in Wrenches, of which the following is a specification, reference being had to the accompanying drawings.

10 This invention comprehends certain new and useful improvements in tools and relates particularly to a wrench of the sliding jaw quick adjustment type.

The invention has for its primary object a simple, durable, and efficient construction of device of this character in which the movable jaw which is mounted to slide along the toothed shank, is provided with a pivotally mounted locking bar having teeth 20 designed to interlock with the teeth of the shank whereby the two jaws may be held in rigid relation to each other upon the work, a yoke encircling the shank and formed with laterally spaced lugs between which the 25 handle portions of the locking bar is adapted to fit, whereby all strains will be relieved from the pivot thereof.

And the invention also aims to generally improve devices of this class so as to render them more useful and commercially desirable.

With these and other objects in view, as will more fully appear as the description proceeds, the invention consists in certain 35 constructions, arrangements and combinations of the parts that I shall hereinafter fully describe and claim.

For a full understanding of the invention, reference is to be had to the following description and accompanying drawing, in which—

Figure 1 is a side elevation of a wrench constructed in accordance with my invention, a portion of the movable jaw being 45 broken away.

Fig. 2 is a top view of a portion of the wrench.

Fig. 3 is a transverse sectional view on line 3—3 of Fig. 1.

50 Corresponding and like parts are referred to in the following description and designated in all of the views of the accompanying drawing by like reference characters.

55 Referring to the drawing, the numeral 1 designates the shank of my wrench and 2

the handle which is secured upon one end of the shank in any desired way, the handle being made either of wood or metal and being preferably formed with a flattened 60 side 3. 4 designates the fixed jaw which is secured on the other end of the shank 1.

A movable jaw 5 is mounted to slide on the shank 1 and is formed, as shown, with a recess 6, in which the reduced end 7 of a 65 locking bar 8 is received, said reduced end being pivotally secured in the recess by a transversely extending rivet or pintle, as shown. The locking bar 8 is formed intermediate of its ends with teeth 9 designed 70 to interlock with the corresponding bevel teeth 10 that are formed on the shank 1 so that after the movable jaw has been properly adjusted toward the fixed jaw and the two jaws engaged with the work, the engagement of the teeth 9 and 10 will hold 75 the movable jaw 1 rigidly in position and the nut or the like may thus be easily turned.

The locking bar 8 is formed with a handle 80 portion 11 which is designed, in the operative position of said bar, to extend along the flattened side 3 of the main handle 2, as clearly illustrated in the drawing.

Preferably, a brace bar 12 is welded or 85 otherwise rigidly secured at one end to the heel end of the fixed jaw 4, and extends parallel with the shank and in spaced relation thereto, the other end of said brace bar being welded or otherwise secured to an 90 extended portion of a yoke 13 which encircles the shank at one end of the handle 2 and thus forms an abutment piece for the adjacent end of said handle. The bar 12 serves as an additional support for the fixed 95 jaw 4 and also prevents straining of said jaw when the device is employed in connection with unusually heavy work as the strain on the jaw 4 will be carried to the handle 2. The yoke 13 is formed with 100 laterally spaced retaining lugs 14 between which the handle portion of the locking bar 8 is adapted to fit when the bar is in its operative position, whereby all lateral stresses or strains on the bar and its pintle or pivot, 105 are compensated for.

15 designates a leaf spring which is preferably secured by a screw or similar fastening device 16 to the movable jaw 5 and which has its free end extending along the 110 locking bar 8 so as to exert tension thereon in a direction to move the bar into operative

engagement with the toothed shank 1 so as to securely hold the parts as against accidental displacement. Not only does the bar 12 serve as a brace between the jaw 4 and the yoke 13, but it serves as a finger or thumb guard so that the movable jaw may be quickly adjusted by one hand of the operator while the thumb, for example, of the operator, remains in proper gripping relation on the bar 12 and the movement of the fixed jaw will not require the operator's thumb to be removed while said jaw is being adjusted.

While the accompanying drawing illustrates what I believe to be the preferred embodiment of my invention, it is to be understood that the invention is not limited thereto but that various changes may be made in the construction, arrangements and proportions of the parts without departing from the scope of the invention as defined in the appended claim.

What I claim, is:

As a new article of manufacture, a

wrench comprising a shank provided with a handle at one end and with a fixed jaw at its opposite end, said fixed jaw extending beyond opposite sides of the shank, a yoke embracing the shank and abutting the inner end of the handle, a portion of said yoke extending rearwardly from the shank, a movable jaw mounted on the shank and positioned intermediate the fixed jaw and the handle, co-acting means carried by the shank and movable jaw for locking the movable jaw to the shank at points intermediate the length of the shank, and a brace bar secured to the heel end of the fixed jaw and to the extended portion of the yoke, said brace bar being substantially parallel to the shank and in spaced relation thereto and free from the movable jaw.

In testimony whereof I hereunto affix my signature in the presence of two witnesses.

HARRY H. GARDNER.
